SLIP GUIDE FOR BINDING STRAPS

George C. Anderson, Portland, Oreg., assignor to Anderson Die & Manufacturing Co., Portland, Oreg.

Filed Oct. 3, 1960, Ser. No. 62,353

Term of patent 14 years

(Cl. D54—11)

FIG.1

FIG.2

FIG.3

FIG. 1 is a view in top plan of a slip guide for binding straps, showing my new design.

FIG. 2 is a view in front elevation of the slip guide for binding straps of FIG. 1.

FIG. 3 is a view in side elevation of the slip guide for binding straps of FIG. 1. The undisclosed side of the slip guide for binding straps is substantially plain in appearance.

I claim:

The ornamental design for a slip guide for binding straps as shown and described.
